(57) **CLAIM**

We claim the ornamental design for a cover for air purifier, as shown and described.

DESCRIPTION

FIG. 1 is a top perspective view of a first embodiment of a cover for air purifier showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 1;

FIG. 10 is another top perspective view thereof with the central circle in an open position;

FIG. 11 is another top perspective view thereof showing the cover for air purifier attached to an example air purifier;

FIG. 12 is an enlarged view of the encircled portion 12 in FIG. 11;

FIG. 13 is a top perspective view of a second embodiment of a cover for air purifier showing our new design;

FIG. 14 is a front view thereof;

FIG. 15 is a rear view thereof;

FIG. 16 is a left-side view thereof;

FIG. 17 is a right-side view thereof;

FIG. 18 is a top view thereof;

FIG. 19 is a bottom view thereof;

FIG. 20 is an enlarged view of the encircled portion 20 in FIG. 13;

(Continued)

FIG. 21 is a top perspective view of a third embodiment of a cover for air purifier showing our new design; FIG. 22 is a front view thereof; FIG. 23 is a rear view thereof; FIG. 24 is a left-side view thereof; FIG. 25 is a right-side view thereof; FIG. 26 is a top view thereof; FIG. 27 is a bottom view thereof; and,

FIG. 28 is another top perspective view thereof with the central circle in an open position.

The evenly-dashed broken lines in the figures show portions of the cover for air purifier which form no part of the claimed design.

The dot-dash broken lines encircling portions of the claimed design that are illustrated in enlargements form no part of the claimed design.
